UNITED STATES PATENT OFFICE.

WILLIAM EDWARD MARTIN, OF STAMFORD, ENGLAND.

ROTARY PUMP.

Application filed April 9, 1924. Serial No. 705,359.

To all whom it may concern:

Be it known that I, WILLIAM EDWARD MARTIN, a subject of the King of Great Britain, residing at Rock House, Scotgate, 5 Stamford, in the county of Lincoln, England, have invented a new and useful Improvement in Rotary Pumps, of which the following is a specification.

The invention relates to that type of 10 rotary pump, air compressor and the like, having a fixed cylinder, a cylindrical piston of smaller diameter which is moved in an eccentric path around the interior wall of the cylinder, a slide pivoted to the piston 15 and moving in a plane which passes diametrically through the fixed cylinder, suction and delivery ports in close proximity to the said slide and walls by which the slide is guided.

20 According to the present invention, a plurality of such pumps are arranged side by side in a single case divided from each other by a rotating diaphragm fixed with respect to the eccentrics and the driving 25 shaft.

Upon the driving shaft are two end discs fitting the interior of the cylinder. Suitable means are provided for connecting the driving shaft, the end discs, the diaphragm 30 and the eccentrics all rigidly together. According to the preferred embodiment of the invention one end disc is in contact with a shoulder on the driving shaft and the other disc is pressed tightly towards the said 35 shoulder by means of a nut on the driving shaft.

The invention is illustrated in the accompanying drawings in which

Fig. 1 is a section taken on the line 3—3 40 showing a modified construction and showing, at one end, the cover for the piston slide broken away.

Fig. 2 is a section on the lines 4—4, 4—4, of Fig. 1.

45 As shown in the drawings, *a* is a driving shaft having two eccentrics *b b* keyed thereon. *c c* are fixed and floating bushes surrounding the eccentrics. *d d* are the eccentric pistons mounted upon the bushes 50 *c c*. *e* is the cylinder casing having a front cover *e¹* and a rear cover *e²*.

A diaphragm *f* is fixed with relation to the driving shaft *a* and as shown is formed integral with the eccentrics *b b*. *g* is a 55 slide of the same width as the eccentric piston *d* and having a head *g¹* mounted within

a suitable bearing in the eccentric piston *d*. *h* is a suction port and *h¹* a delivery port of the same length as the eccentric piston *d*. The two suction ports and two delivery ports are divided by a part *e³* of the cylinder *e*. *i* is a wall dividing the suction and the delivery ports and formed integral with the base of the pump. The slide *g* is kept in contact with the wall *i* by means of the wall *i¹* which is held in position by the bolt *i²*, passing through the distance collar *i³* and screwing into a boss on the wall *i*. Each slide *g* is formed with a slot *g²* to pass over the distance collar *i³*.

When the shaft *a* is driven it causes the pistons to move around the interior of the cylinder casing *e* and to rock upon the head *g¹* of the slide *g* in known manner.

The shaft *a* is provided with end discs *j j¹*. The disc *j¹* is in contact with a shoulder *k* on the driving shaft *a*. The disc *j* is pressed towards its adjacent piston by means of a nut *h¹* which screws on to a thread formed on the driving shaft *a*. Each disc is turned down to form a shoulder *j²* on its outer surface which is in contact with the cylinder cover.

In this construction, as the end discs *j, j¹* the eccentrics *b b* and the diaphragm *f* are 85 all fixed with respect to the driving shaft *a* there will be equal and opposite end pressure against the diaphragm *f* and an end disc *j* or *j¹* as each piston *d* is delivering but no end pressure between the pistons and the 90 ends of the cylinder as in known constructions.

The cover *e²* is provided with a lubricating device *l* and the shaft *a* is bored at *a¹* to convey the lubricant between the pistons *d d*, the bushes *c c* and the slide *g* and its head *g¹*.

What I claim as my invention is:—

1. An improved rotary pump, air compressor and the like having in combination 100 a driving shaft, a plurality of eccentrics keyed upon the driving shaft, a piston slidably mounted on each eccentric and moving in contact with the inner wall of the cylinder, a diaphragm dividing each pair of 105 pistons and fixed with relation to the driving shaft, end discs upon the driving shaft between the pistons and the ends of the cylinder, a slide pivoted to each piston and moving on a plane which passes diametrically through the cylinder, a suction port on one side of each slide, a delivery port on the 110

other side of each slide, two walls dividing the suction and delivery ports between which the slides are located, and means for rigidly connecting together the end discs, 5 diaphragm, eccentrics and shaft, substantially as set forth.

2. An improved rotary pump, air compressor and the like having in combination a driving shaft, a plurality of eccentrics keyed 10 upon the driving shaft, a piston surrounding each eccentric and rotating in contact with the inner wall of the cylinder, a diaphragm dividing each pair of pistons and fixed with relation to the driving shaft, end discs upon 15 the driving shaft between the pistons and the ends of the cylinder, a slotted slide pivoted to each piston and moving on a plane which passes diametrically through the cylinder, a suction port on one side of each slide, a 20 delivery port on the other side of each slide, two walls dividing the suction and delivery ports between which the slides are located, distance collars separating the walls and bolts passing through each distance collar, substantially as set forth.

3. An improved rotary pump, air compressor and the like having in combination a driving shaft, a plurality of eccentrics keyed upon the driving shaft, a piston surrounding each eccentric and rotating in contact with the inner wall of the cylinder, a diaphragm dividing each pair of pistons and fixed with relation to the driving shaft, end discs upon the driving shaft between the pistons and the ends of the cylinder, a collar on 30 the driving shaft against which one end disc abuts, a nut screwed on the driving shaft which is screwed against the other end disc, a slotted slide pivoted to each piston and 35 moving on a plane which passes diametrically through the cylinder, a suction port on one side of each slide, a delivery port on the other side of each slide, two walls dividing the suction and delivery ports between 40 which the slides are located, distance collars separating the walls and bolts passing through each distance collar, substantially as set forth.

4. An improved rotary pump, air compressor and the like having in combination a 50 driving shaft, a plurality of eccentrics keyed upon the driving shaft, a piston surrounding each eccentric and rotating in contact with the inner wall of the cylinder, a diaphragm dividing each pair of pistons 55 and fixed with relation to the driving shaft, end discs upon the driving shaft between the pistons and the ends of the cylinder, a shoulder on the outer face of each end disc, a slotted slide pivoted to each piston and moving on a plane which passes diametrically 60 through the cylinder, a suction port on one side of each slide, a delivery port on the other side of each slide, two walls dividing the suction and delivery ports between which 65 the slides are located, distance collars separating the walls and bolts passing through each distance collar, substantially as set forth.

5. An improved rotary pump, air compressor and the like having in combination a driving shaft, a plurality of eccentrics keyed upon the driving shaft, a piston surrounding each eccentric and rotating in contact with the inner wall of the cylinder, a 70 diaphragm dividing each pair of pistons and fixed with relation to the driving shaft, end discs upon the driving shaft between the pistons and the ends of the cylinder, a shoulder on the outer face of each end disc, 75 a collar on the driving shaft against which one end disc abuts, a nut screwed on the driving shaft which is screwed against the other end disc, a slotted slide pivoted to each 80 piston and moving on a plane which passes diametrically through the cylinder, a suction port on one side of each slide, a delivery port on the other side of each slide, two 85 walls dividing the suction and delivery ports between which the slides are located, distance collars separating the walls and bolts 90 passing through each distance collar, substantially as set forth.

In witness whereof I have hereunto set my hand.

WILLIAM EDWARD MARTIN.
